US0D1011657S

(12) **United States Design Patent** (10) **Patent No.:** **US D1,011,657 S**
(45) **Date of Patent:** **** Jan. 16, 2024**

(54) **PAINT BRUSH CLEANER**

(71) Applicant: **Shenzhen Kaduo Industrial Co., Ltd.**,
Shenzhen (CN)

(72) Inventor: **Jiping Liao**, Hunan (CN)

(**) Term: **15 Years**

(21) Appl. No.: **29/887,964**

(22) Filed: **Mar. 27, 2023**

(30) **Foreign Application Priority Data**

Mar. 17, 2023 (CN) 202330127026.2

(51) **LOC (14) Cl.** **15-05**

(57) **CLAIM**

The ornamental design for a paint brush cleaner, as shown and described.

DESCRIPTION

FIG. 1 is a perspective view of a paint brush cleaner showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof; and,

FIG. 8 is bottom plan view of a paint brush cleaner thereof. The broken line showing of the paint brush cleaner is for the purpose of illustrating article and forms no part of the claimed design.

1 Claim, 8 Drawing Sheets
